UNITED STATES PATENT OFFICE.

FRANK IVANHOE STILES, OF SAUK RAPIDS, MINNESOTA.

CLOTH MEASURING AND CUTTING MACHINE.

SPECIFICATION forming part of Letters Patent No. 752,120, dated February 16, 1904.

Application filed May 4, 1903. Serial No. 155,571. (No model.)

To all whom it may concern:

Be it known that I, FRANK IVANHOE STILES, a citizen of the United States, residing at Sauk Rapids, in the county of Benton and State of Minnesota, have invented certain new and useful Improvements in Cloth Measuring and Cutting Machines, of which the following is a specification.

My invention relates to machines for measuring and cutting cloth. One of its principal objects is to provide an automatic registering-machine of the character referred to which shall be peculiarly adapted for use in the inventoring of stock as well as the retailing of goods over the counter.

A further object is to provide a simple, efficient, easily erected, and inexpensive machine of the character stated.

Other objects and advantages will be hereinafter discussed.

The invention consists in certain novel constructions, combinations, and arrangements of parts hereinafter described in more or less detail, and finally pointed out in the claims hereinafter appended.

The nature, characteristic features, and scope of the invention will be more fully understood from the following description, taken in connection with the accompanying drawings, forming a part hereof, wherein—

Figure 1 is a perspective view of a self-registering cloth measuring and cutting machine constructed in accordance with my invention. Fig. 2 is a vertical sectional view of the same. Fig. 3 is a perspective view of the device for gripping the end of the cloth and attaching same to the winding-reel. Fig. 4 is a perspective view of the adjustable roll and toggle-levers for lowering and elevating the same. Fig. 5 is a perspective view of the lugs for gripping the center rod to the bolt of cloth, and Fig. 6 is a view of the registering-dial and intermediate gearing.

Referring to the machine, A represents a suitable basal support from which rise the standards A' A² A³ A⁴ A⁵ A⁶. The standards A' are forked at their upper end, as at a, and

serve to carry the bolt of cloth X in such wise that the latter may be turned. Any suitable means may be employed for the purpose; but I employ a cylindrical rod a', disposed axially of the bolt and having the toothed clamping-lugs a² disposed at each end of the bolt for gripping the latter, so that it may be rotated in unison with said rod. The clamping device or lugs a² are shown in detail in Fig. 4, where one is shown provided with a cylindrical perforation and with a spline a³ for permanently securing it in respect of the grooved rod a', and whereof the other is provided with a set-screw a⁴ to render it adjustable along the length of said rod. The rod a' is also provided at one end with a collar a⁵ for holding it securely in the fork. It will be understood, of course, that extra rods a' may be supplied to accommodate different pieces of cloth.

The standards A² are in the form of sleeves or tubes adapted to receive the telescoping rods b. The rods b afford bearings in their upper ends for the axis of a roll B, over which the cloth travels. It is important that this roll be adjustable in a vertical direction, and I make suitable provision for this, as follows: The standards A² are provided with slots b' to 70 constitute ways for the studs or projections b² of the rods b. The studs b² are connected with the tubular standards A² by means of toggle-levers b³, the toggle-levers being themselves connected by a transverse bar or connecting-rod b⁴. It will thus be apparent that by the provision of a handle or its equivalent b⁵, through the medium of the toggle-levers b³, the rods b may be raised or lowered, as may be desired.

The standards A² support a table c, on one edge of which is secured a stationary knife-blade c', which co-operates with a shearing member or knife C. The knife C has a horizontally-flanged upper edge c⁶ to stiffen it and is slightly curved, as shown in Fig. 1, and is pivoted in a support c⁷ at one end of the table upon a horizontal spindle c⁸. A handle c⁹ may be provided on the knife for manipulating it,

and a coil-spring c^4 , placed upon the spindle c^5 , is also provided for normally maintaining said knife elevated.

Intermediate the standards A^3 and A^2 and A^2 and A' are the supports or standards A^5 and A^6 , which carry the coincident braking or guide rolls D .

One of the standards A^4 at the front of the machine affords bearings for a winding-reel E .
Also journaled in said standards is a shaft e , having a crank e' at one end thereof for facility in turning it and having a sprocket-wheel e^2 connecting, by means of a chain e^3 , with a smaller sprocket-wheel e^4 on the shaft of the winding-reel E .

Referring to Figs. 1 and 3, F represents the cloth-end gripping device, consisting of a plate or body f , having three coincident spring-clasps f^1 connected thereto by means of toggle-levers f^2 , the levers of the respective clasps being connected by a rod f^3 for simultaneous movement. The points f^5 of the clasps engage the end of the cloth, and in order to guide the cloth evenly under said points I employ the transverse wire f^6 .

Mounted on the top of the standard A^5 , preferably to one side of the machine, is the registering device G . The location of the registering device is of course dependent on the width of the cloth. Said registering device is supported upon a flat spring g^1 , secured to the standard A^5 , said spring permitting the registering device to adjust itself in respect of the intermediate roll. The registering device consists of a dial or indicator, Fig. 6, calibrated on a scale of thirty-six points around its circumference. Two hands g g' are provided, whereof one indicates fractions of a yard in inches, and whereof the other registers yards. Otherwise stated, the revolution of the hand g indicates one yard, and one revolution of hand g' represents thirty-six yards. g^2 represents suitable intermediate gearing for accomplishing this result. g^3 represents a suitable spring for returning the hands to their original positions—for instance, when the cloth is released. g^4 represents a wheel suitably journaled and having its periphery provided with points g^5 , adapted to engage the cloth.

The operation of the machine may be described as follows: The rod a' being applied as before explained and the bolt ω mounted in the forked standards A' , the gripping device is then applied to the free end of the cloth before any is unrolled, and said free end is carried under rolls D and over roll B until the end of the cloth is at the cutting-line. Then the roll B is raised by means of toggle-levers b^3 , which carry the goods up and against the measuring device g^4 , (which will thus only measure the goods that pass the cutting-

line.) Then the gripping device is carried forward and hooked on the reel by means of the hooks f^7 . When a sufficient length of cloth 65 has been measured off, the operator pulls down the shear-knife C , and after cutting the cloth the knife springs back again. By lowering the roll B by means of the levers b^3 the uncut portion of the goods is released, and the measuring device returns to its starting-point. The arbor E' of the reel is supported at one end only, (see Fig. 1,) so that after the goods are wound on said reel they may be stripped off in a folded state. The arbor E' is shown solid 75 in Fig. 2; but it will be understood that it may be hollow.

It will be obvious to those skilled in the art to which the invention appertains that modifications may be made in details without departing from the spirit and scope of same. Hence I do not limit myself to the precise construction and arrangement of parts herein described; but,

Having thus described the nature and objects of the invention, what I claim as new, and desire to secure by Letters Patent, is—

1. In a cloth measuring and cutting machine, the combination of supports in which the bolt may be rotated, brake-rolls, a roll over which the cloth passes intermediate the brake-rolls, means for lowering and elevating said intermediate roll, registering mechanism coacting with said intermediate roll, shearing apparatus, and a winding-reel, substantially as described.

2. In a cloth measuring and cutting machine, the combination of supports in which the bolt may be rotated, brake-rolls, a vertically-adjustable roll intermediate the brake-rolls over which the cloth passes, registering mechanism coacting with said intermediate roll, shearing apparatus, a winding-reel, and means substantially as described for connecting the cloth with the winding-reel.

3. In a cloth measuring and cutting machine, the combination of forked standards, a cylindrical but grooved rod adapted to be passed through a bolt of cloth and to rotate in said standards, said rod having a collar adjacent to one of said standards, and a toothed lug a^3 provided with a spline, said lug effecting a rigid connection between the bolt and rod substantially as described.

4. The combination in a cloth measuring and cutting machine of a bolt-carrying frame, a winding-reel and means for attaching the cloth to the reel consisting of a plate having hooks to engage the reel and clasps to engage the cloth, with means for simultaneously locking or releasing the clasps, substantially as described.

5. The combination in a cloth measuring and cutting machine, of a frame in which the bolt

may rotate, a pair of guide-rolls, tubular standards, rods telescoping said standards, means for adjusting both rods simultaneously in respect to the standards, a roll over which the cloth travels intermediate the guide-rolls and journaled in said rods, a spur-wheel adapted to engage and be rotated by the traveling cloth when said intermediate roll is in its elevated position, registering mechanism coöperating

with said spur-wheel, shearing apparatus, and a winding-reel, substantially as described.
In testimony whereof I affix my signature in presence of two witnesses.

FRANK IVANHOE STILES.
